UNITED STATES PATENT OFFICE.

WILLIAM EVENSEN, OF CHICAGO, ILLINOIS, ASSIGNOR TO GOSS PRINTING PRESS COMPANY, A CORPORATION OF ILLINOIS.

FOLDING MECHANISM.

Application filed March 16, 1923. Serial No. 625,579.

The invention relates to a novel and useful rotary folding mechanism, and more especially in certain of its aspects to such a mechanism for rapidly, easily and correctly folding newspapers and the like which vary greatly in the number of pages.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a fragmentary view, partly in elevation and partly in section of a folding mechanism constructed in accordance with the invention, and is taken substantially on the line 1—1 of Fig. 2;

Fig. 2 is a view, partly in elevation and partly in vertical section taken on the line 2—2 of Fig. 1;

Fig. 3 is a horizontal view, partly in plan and partly in section, taken substantially on the line 3—3 of Fig. 2;

Fig. 4 is a detached detail partly in elevation and partly in section taken on the line 4—4 of Fig. 6;

Fig. 5 is a view similar to Fig. 4, but showing a lock-nut on the adjustment screw;

Fig. 6 is a section, on an enlarged scale, taken substantially on the line 6—6 of Fig. 2;

Fig. 7 is a fragmentary vertical section taken substantially on the line 7—7 of Fig. 1, but showing the tucking blade cooperating with the folding roller in the folding operation; and

Fig. 8 is a detached perspective view of one of the folding roller positioning wedges.

The present preferred and herewith illustrated exemplary embodiment of the invention comprises certain constructions which are well known and certain features in the nature of improvements thereon.

A rotary folding member carries a rotary

folding or tucking blade, and also receives upon itself a stack or bundle of sheets, such as those of a newspaper. Adjacent to and cooperating with the foregoing is a pair of folding rollers, and the tucking blade is operated by suitable mechanism, preferably a slotted rotary cam, to tuck the central or other median part of the stack or group of sheets between the folding rollers, whereby a transverse fold is made therein and they are fed off between the folding rollers. All the foregoing structure is old and well known.

In the present invention, the two cooperating folding rollers and their mountings and drives are constructed so that one of the rollers is movable toward and away from the other roller to vary the distance therebetween for newspapers or other like products of different numbers of sheets or pages. To enable the folding or tucking blade in making the fold to strike always centrally of the distance between the folding rollers, means are provided for varying the position of the folding blade relatively to its mounting, which is rotatably carried upon the rotary folding member already described. More particularly, the tucking blade is fixed in a carrier, which is journaled on the rotary folding cylinder and is actuated by the rotary cam to tuck the sheets between the folding rollers. By the present invention, the tucking blade is variably positionable on its carrier, preferably angularly, so that the blade may strike centrally between the folding rollers notwithstanding that one roller is moved to and fro to accommodate newspapers of different thicknesses.

Other features of the invention will be primarily set forth in connection with the following detailed description, and it will be understood that the foregoing general description and the following detailed description are both explanatory and exemplary, but are not restrictive of the invention.

Referring now in detail to the embodiment of the invention illustrated by way of example in the accompanying drawings, the member which carries the sheet or usually the group or bundle of sheets preparatory to folding, and from which they are folded off, comprises a cylinder 1, the shaft 2 of which is journaled in bearings 3 at either end thereof, respectively, upon the side frames 4 of the machine. Suitable means are provided

for holding the group or stack of sheets upon the cylinder, which means may be of any suitable kind or form but are shown herein conventionally as grippers 5 adapted to engage with the lead end of the group or bundle of sheets. There are two such sets of grippers shown, a semi-circumference apart, the cylinder being also provided with two folding blades. A cutting cylinder 6 is shown conventionally journaled in bearings 7 on the machine frame, but it forms no part of the present invention, but may be used to cut the sheets from the associated webs at this point, if desired.

15 Rotatably mounted upon the cylinder 1 are two folding or tucking blades 10 and 11, one being shown at rest in Fig. 2, and the other performing the folding operation, in Fig. 7 of the drawing. As embodied, the 20 folding blades are double-edged, and make a half-revolution relatively to the rotating folding cylinder for each fold. A shaft 12 is journaled in bearings 13 near either end thereof, these bearings being mounted in 25 the folding cylinder 1. Fixed to the shaft 12 is a blade-carrying body 14, extending in both directions diametrically from the shaft, and each of these parts is adapted to carry a folding blade. A folding blade 15 is 30 mounted on one side and a folding blade 16 mounted on the other side thereof. These blades may, if desired, be interchangeable with others which are wider or narrower, or the blades may be made radially adjustable 35 relatively to the body 14.

In the embodied form and in accordance with one feature of the invention, and having in view more especially the application of the invention to a mechanism wherein 40 one of the folding rollers is variably and regulably positionable relatively to a cooperating folding roller journaled in fixed position, so as to vary the distance between the folding rollers for groups or bundles 45 consisting of different numbers of sheets. A common example of this is where a newspaper may vary from day to day from say four to sixty-four pages. In connection with such folding rollers, means are provided 50 for very slightly and very accurately positioning the tucking blade relatively to its carrier. This change of position is preferably relatively angularly, that is, with reference to its shaft and the actuating means 55 carried thereby, which cooperate with the actuating cam later to be described.

As embodied, the shaft 12 has fixed to or integral with one end thereof a circular disk 20, which disk fits closely but rotatably into a circular recess let into the inner face of an oblong head 21. Means are provided for holding the disk 20 and the head 21 in the described relation while permitting slight angular adjustment therebetween. As embodied, a plurality of tap bolts 24, pass

through apertures in the disk 20, which apertures are somewhat larger than the bolts, the heads 25 of the bolts resting or pressing against the exterior face of the disk 20. The inner ends of the bolts 24 are reduced in diameter and are screw-threaded into tapped screw-threads in the head 21. Thus they have a shouldered seat on the inner face of the annular recess in the head 21 and thus will hold without binding the 75 disk 20.

Further, as embodied, the head 21 is cut away at one side, as is shown at 27, and the disk 20 has an outwardly extending lug or arm 28, projecting into the opening 27 in 80 the head 21. Screw-threaded into this lug 28 is a screw bolt 29. The screw bolt projects from either side of the lug, and has its head bearing against one side face 30 of the opening 27 and its point bearing against 85 the opposite side face 31 of said opening. Thus by turning the finely threaded screw 29, the tucking blades 15 and 16 may be very nicely angularly adjusted relatively to the head 21.

90 The head 21 is provided with devices co-operating with suitable actuating means, preferably a rotary cam of the kind shown in United States Patent No. 871,038 dated Nov. 12, 1907, to H. P. Husby. For this 95 purpose, the head 21 is provided at either end thereof with two pins or rollers 33 and 34, fixed thereto by suitable means, such as bolts 35 and 36, respectively, which are shouldered on the outer face of the head 21 100 and have reduced portions 40 and 37 passing therethrough, and have nuts 38 and 39, respectively, screw-threaded on the inner ends thereof.

The embodied form of cooperating means 105 comprises a cam disk 54, fixed to a gear wheel 55, which is rotatably mounted on a stub shaft 56. Shaft 56 is carried in a hub 65, and is held in position by a nut 66, screw-threaded on the exterior end of the 110 shaft. Cam disk 54 is provided with a plurality of actuating slots, shown as three in number, 57, 58, and 59, these slots being preferably non-radially disposed, as shown in Fig. 2. The cam disk is fixed to the gear 115 in any suitable manner, as by tap bolts 60. The gear 55 meshes with a gear wheel 61, fixed on the shaft 2 of the folding cylinder 1.

120 A guide ring 62 is in operative position with respect to the pins 33 and 34 on the head 21 and with respect to the cam 54. As the cylinder 1 rotates, the pins 33 and 34 are both in contact with the ring 62 and the tucking blade is thereby held flat and idle. When the cam disk 54 is reached, the leading pin 33 or 34 enters one of the cam slots, and thereby the shaft 12 is given a half rotation, one of the blades effecting the 125 folding operation with the folding rollers. 130

At the end of this half revolution, the actuating pins 33 and 34 again ride out on ring 62, holding the tucking blade in inoperative relation during the remainder of the rotation of the folding cylinder 1. Where two tucking blade mechanisms are provided, a semi-circumference apart, there are two folding operations for each rotation of the cylinder 1.

Referring now to the embodied form of the folding rollers, and their mounting and actuating connections, a folding roller 70 has its shaft 71 journaled in fixed bearings 72 and 73 upon the machine frame. The bearing 73 has therewithin a sleeve 74, encircling the shaft 71. A gear pinion 75 is fixed on shaft 71, and is driven in any suitable manner. Fixed also on shaft 71 is a gear wheel 76, which meshes with a gear wheel 77, fixed on the shaft 78 of the cooperating folding rollers 79, although so far as concerns most features of the invention the folding roller 79 can be driven in any desired manner and without direct gear connection to the folding roller 70.

In the embodied form of mounting for the movable or positionable roller 79, it is also preferably provided with resilient spring action. As embodied, the ends of its shaft 78 are journaled, respectively, in hubs 86 at either end thereof. These hubs are provided, respectively, with radially-projecting, cylindrical wrists or heads 87, which are reciprocably mounted in apertures in the inner heads of hollow cylinders 88.

Fixed to, and preferably integral with the wrists 87 are rods 90, projecting rearwardly therefrom and located within the cylinders 88, the rear ends thereof projecting from the rear heads of the respective cylinders. Helical springs 91 encircle the respective rods 90 within their cylinders 88 and are in compression between the inner ends of the wrists 87 and the rear heads of the cylinders 88. The cylinders 88 are mounted on the machine frame by suitable means, such as bolts 93.

Further, as embodied, positioning wedges 100 are beveled horizontally and outwardly, and have recesses 101 therein and these recesses encircle the inner ends of the respective rods 90. Nuts 102 are screw-threaded onto the ends of rods 90 outside of the positioning wedges 100 so that the parts will move together. The nuts 102 serve also to regulate the action of the respective springs 91. Each wedge 100 has a hub 104 within which is a longitudinally-extending, screw-threaded aperture 105. A screw-rod 106, threaded right and left, is screwed into the apertures 105, and is provided with a bearing or support 107 on the machine frame. The structure, however, is carried on the rods 90 by means of the slots 101.

A hand-wheel 108 is fixed on the rod 106 for rotating same. Thus the roller 79 may be very nicely positioned with respect to roller 70 to provide the desired folding opening therebetween for the particular number or thickness of sheets being folded, and by the screw 29, the blade may be likewise timed so that the tucking blade will always strike exactly midway in the space between the folding rollers. Thus through the hand-wheel 108 the space between the folding rollers 70 and 79 may be varied, as desired, to suit the number of sheets to be folded, and by means of the screw bolt 29, the folding blade may be made to strike accurately absolutely centrally of the space between the folding rollers.

The invention in its broader aspects is not limited to the specific mechanisms shown and described, but departures may be made therefrom within the scope of the accompanying claims without departing from the principles of the invention and without sacrificing its chief advantages.

What I claim is:—

1. A folding mechanism including in combination a rotary folding member, a pair of rotary tucking blades carried thereby, a pair of cooperating folding rollers, means for actuating the tucking blades, and means for variably and independently positively positioning the tucking blades relative to said rotary folding member to change their relation to the folding rollers.

2. A folding mechanism including in combination a rotary folding member, a pair of rotary tucking blades carried thereby, a pair of cooperating folding rollers, means for actuating the tucking blades, and means for variably, angularly, and independently positively positioning the tucking blades relative to said rotary folding member to change their relation to said folding rollers.

3. A folding mechanism including in combination a rotary folding member, a pair of rotary tucking blades carried thereby, a pair of cooperating folding rollers, rotary means for actuating the tucking blades, and means for variably and independently positively positioning the tucking blades relative to said rotary folding member to change their relation to the folding rollers.

4. A folding mechanism including in combination a rotary folding member, a plurality of rotary tucking blades carried thereby, a pair of relatively adjustable cooperating folding rollers, rotary means for actuating the tucking blades, and means for variably, angularly, and independently positively shifting the tucking blades relative to said rotary folding member to change their relation to the folding rollers.

5. A folding mechanism including in combination a rotary folding member, a rotary

- tucking blade carried thereby, a pair of cooperating folding rollers, means for regulably varying the distance between the folding rollers for papers of different thicknesses, 5 means for actuating the tucking blade, and means for variably and positively shifting the tucking blade relatively to said rotary folding member to change its relation to the folding rollers.
10. 6. A folding mechanism including in combination a rotary folding member, a rotary tucking blade carried thereby, a pair of cooperating folding rollers, means for regulably varying the distance between the folding rollers for papers of different thicknesses, means for actuating the tucking blade, and means for variably angularly and positively shifting the tucking blade relatively to said rotary folding member to change its relation to the folding rollers.
15. 7. A folding mechanism including in combination a rotary folding member, a rotary tucking blade carried thereby, a pair of cooperating folding rollers, one roller being in fixed position and the other being movable to vary the distance between them for papers of different thicknesses, means for actuating the tucking blade, and means for variably and positively shifting the tucking blade relatively to said rotary folding member to change its relation to the folding rollers.
20. 8. A folding mechanism including in combination a rotary folding member, a rotary tucking blade carried thereby, a pair of cooperating folding rollers, one roller being in fixed position and the other being movable to vary the distance between them for papers of different thicknesses, means for actuating the tucking blade, and means for variably angularly and positively shifting the tucking blade relatively to said rotary folding member to change its relation to the folding rollers.
25. 9. A folding mechanism including in combination a rotary folding member, a rotary tucking blade carried thereby, a pair of cooperating folding rollers, means including a rotary slotted cam for actuating the tucking blade, and means for variably and positively shifting the tucking blade relatively to said rotary folding member to change its relation to the folding rollers.
30. 10. A folding mechanism including in combination a rotary folding member, a pair of rotary tucking blades carried thereby, a pair of cooperating folding rollers, means including a rotary slotted cam for actuating the tucking blades, and means for variably, angularly, and independently positively moving the tucking blades relative to said rotary folding member to change their relation to the folding rollers.
35. 11. A folding mechanism including in combination a rotary folding member, a pair of rotary tucking blades carried thereby, a pair of cooperating folding rollers, means including a rotary slotted cam for actuating the tucking blades, and means for variably angularly and positively moving the tucking blade relatively to said rotary folding member to change its relation to the folding rollers.
40. 12. A folding mechanism including in combination a rotary folding member, a pair of rotary tucking blades carried thereby, a pair of cooperating folding rollers, rotary means including a rotary slotted cam for actuating the tucking blades, and means for variably and independently positively moving the tucking blades relative to said rotary folding member to change their relation to the folding rollers.
45. 13. A folding mechanism including in combination a rotary folding member, a rotary tucking blade carried thereby, a pair of cooperating folding rollers, means for regulably varying the distance between the folding rollers for papers of different thicknesses, means including a rotary slotted cam for actuating the tucking blade, and means for variably and positively moving the tucking blade relatively to said rotary folding member to change its relation to the folding rollers.
50. 14. A folding mechanism including in combination a rotary folding member, a rotary tucking blade carried thereby, a pair of cooperating folding rollers, means for regulably varying the distance between the folding rollers for papers of different thicknesses, means including a rotary slotted cam for actuating the tucking blade, and means for variably angularly and positively moving the tucking blade relatively to said rotary folding member to change its relation to the folding rollers.
55. 15. A folding mechanism including in combination a rotary folding member, a rotary tucking blade carried thereby, a pair of cooperating folding rollers, one roller being in fixed position and the other being movable to vary the distance between them for papers of different thicknesses, means including a rotary slotted cam for actuating the tucking blade, and means for variably and positively moving the tucking blade relatively to said rotary folding member to change its relation to the folding rollers.
60. 16. A folding mechanism including in combination a rotary folding member, a rotary tucking blade carried thereby, a pair of cooperating folding rollers, one roller being in fixed position and the other being movable to vary the distance between them for papers of different thicknesses, means including a rotary slotted cam for actuating the tucking blade, and means for variably angularly and positively moving the tucking blade relatively to said rotary folding member to change its relation to the folding rollers.

ber to change its relation to the folding rollers.

17. A folding mechanism including in combination a rotary folding member, a tucking blade carrier rotatably journaled thereon, a tucking blade mounted on the carrier, a pair of cooperating folding rollers, one at least thereof being movable to vary the distance therebetween for folding papers of different thicknesses, means for actuating the tucking blade, and means for angularly and positively moving the tucking blade relatively to its carrier so that the blade may strike centrally between the folding rollers.
18. A folding mechanism including in combination a rotary folding member, a tucking blade carrier rotatably journaled thereon, a tucking blade mounted on the carrier, a pair of cooperating folding rollers, one at least thereof being movable to vary the distance therebetween for folding papers of different thicknesses, means for actuating the tucking blade, and means for positively moving the tucking blade relatively to its carrier so that the blade may strike centrally between the folding rollers.

19. A folding mechanism including in combination a rotary folding member, a tucking blade carrier rotatably journaled thereon, a tucking blade mounted on the carrier, a pair of cooperating folding rollers, one at least thereof being movable to vary the distance therebetween for folding papers of different thicknesses, means including a rotary slotted cam for actuating the tucking blade, and means for angularly positively moving the tucking blade relatively to its carrier so that the blade may strike centrally between the folding rollers.
20. A folding mechanism including in combination a rotary folding member, a tucking blade carrier rotatably journaled thereon, a tucking blade mounted on the carrier, a pair of cooperating folding rollers, one at least thereof being movable to vary

the distance therebetween for folding papers of different thicknesses, means including a rotary cam having a non-radial actuating slot therein for actuating the tucking blade, and means for angularly positively moving the tucking blade relatively to its carrier so that the blade may strike centrally between the folding rollers.

21. A folding mechanism including in combination a rotary folding member, a tucking blade carrier rotatably journaled thereon, a tucking blade mounted on the carrier, a pair of cooperating folding rollers, one at least thereof being movable to vary the distance therebetween for folding papers of different thicknesses, means including a rotary cam having a plurality of actuating slots therein, for actuating the tucking blade, and means for angularly positively moving the tucking blade relatively to its carrier so that the blade may strike centrally between the folding rollers.

22. A folding mechanism including in combination a rotary folding member, a tucking blade carrier rotatably journaled thereon, a tucking blade mounted on the carrier, a pair of cooperating folding rollers, one at least thereof being movable to vary the distance therebetween for folding papers of different thicknesses, means including a rotary cam having a plurality of non-radial actuating slots therein, for actuating the tucking blade, and means for angularly positively moving the tucking blade relatively to its carrier so that the blade may strike centrally between the folding rollers.

23. A folding mechanism comprising folding rollers, a cylinder cooperating therewith, a shaft and a tucking blade carried by the cylinder, a cam for actuating the tucking blade, and means for variably and positively moving the shaft and blade.

In testimony whereof, I have signed my name to this specification.

WILLIAM EVENSEN.
